(57) **CLAIM**

The ornamental design for a forklift fork tip end, as shown and described.

DESCRIPTION

FIG. 1 is an illustrative isometric view of a portion of a forklift truck including a forklift fork tip end showing our new design; FIG. 2 is an isometric view, at an enlarged scale, of the forklift fork tip end including our new design;

FIG. 3 is a top plan view thereof;

FIG. 4 is a side view, with the opposite side view being a mirror image thereof;

FIG. 5 is a bottom plan view thereof; and,

FIG. 6 is a front end elevational view thereof.

Portions of a forklift truck and portions of the forklift fork are shown in broken line in the drawing views and are included merely for illustrative purposes and form no part of the claimed design. The broken lines immediately adjacent to the shaded areas of the drawing views represent unclaimed boundaries of the design. The shading in the drawing views is intended to denote that the oblong outlined areas contrast visibly to the surrounding surfaces.

1 Claim, 2 Drawing Sheets

FIG. 3**FIG. 4****FIG. 5****FIG. 6**
